UNITED STATES PATENT OFFICE.

DAVID ZAIDEN, OF EAST ORANGE, NEW JERSEY.

HULA DOLL.

1.423.383.

Specification of Letters Patent. Patented July 18, 1922.

Application filed May 9, 1921. Serial No. 467,805.

To all whom it may concern:

Be it known that I, DAVID ZAIDEN, a citizen of Russia, residing at East Orange, in the county of Essex and State of New Jersey, have invented certain new and useful Improvements in Hula Dolls; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 This invention relates, generally, to improvements in dolls; and the same has reference, more particularly, to a novel construction of mechanically operated doll adapted to perform movements in simulation
20 of the Hawaiian dance known as the hula dance, and dances of a similar character.

The invention has for its principal object to provide a construction of doll having a novel skirt arrangement pivotally connected therewith in combination with a novel motor device mounted within the interior of the doll body, and a means interconnecting said skirt with said motor device whereby a rhythmic swaying movement of said skirt is produced in simulation of a dance movement.

Other objects of this invention, not at this time more particularly enumerated, will be clearly understood from the following detailed description of the same.

With the objects of this invention in view, the same consists, primarily, in the novel construction of mechanical doll adapted to simulate dance movements as hereinafter set forth; and, furthermore, the invention consists in the novel arrangements and combinations of the various devices and parts, as well as in the details of the construction thereof, all of which will be hereinafter more fully described and claimed.

The invention is clearly illustrated in the accompanying drawings, in which:—

Figure 1 is a back view or elevation of the novel mechanical doll, made according to 50 and embodying the principles of this invention.

Figure 2 is a fragmentary transverse vertical longitudinal section, with the motor device shown in elevation.

55 Similar characters of reference are em-

ployed in all of the hereinabove described views, to indicate corresponding parts.

Referring now to said drawings, the reference character 1 indicates the body of a doll, preferably made of molded material in any suitable design, and provided in its trunk portion 2 with a hollow interior or chamber 3 having openings 4 leading therefrom at its opposite sides at or adjacent to the hips or waist line of said body.

Secured within the chamber or hollow interior 3, and adapted to be inserted therein through an opening 5 provided in the back of the body, is the frame of a mechanical motor device, which is secured in fixed relation to the body by means of supporting brackets 7 secured to the latter, and which possess inwardly off-set portions 8 to which said motor frame 6 is attached. 70

Said motor device comprises a spring- 75
arbor 9 journaled in the upper portion of
the frame 6, said arbor projecting rear-
wardly through said opening 5, and having
on its outer end a winding key 10. The ref-
erence character 11 indicates a spirally 80
wound motor spring, the inner end of which
is secured to said arbor 9, while the outer end
12 is anchored upon or fixed to a cross bar
13 which forms a part of said frame 6.
Journaled upon said arbor 9 is a driving gear
14 adapted to be rotated by said motor spring
by any suitable arrangement commonly em-
ployed in clock spring movements. Jour-
naled in said frame 6 beneath said motor
spring is a spindle 15 upon which is fixed 90

a pinion 16, which meshes with and is driven by said driving gear 14. Also fixed on said spindle 15 is an intermediate gear 17. Journaled in said frame 6 beneath said spindle 15 is another spindle 18 upon which is fixed 95 a pinion 19 adapted to mesh with and be driven by said intermediate gear 17. Fixed on said spindle 18 is a toothed escapement wheel 20. Journaled in said frame beneath said spindle 18 is an arbor 21 upon which is 100 fixed an escapement dog or anchor 22, the latter having an impulse pallet 23 at one end, and a locking pallet 24 at the other end, which alternately cooperate with said toothed escapement wheel 20. Connected 105 with said arbor 21, so as to be oscillated by the escapement mechanism, is a downwardly projecting lever 25. Connected with the free end of said lever 25 is a transverse tubular member or bar 26. Telescopically connected 110

with the respective ends of said bar 26 are oppositely extending tubular arms 27 and 28. Said arms 27 and 28 are retained in their attached relation to said bar 26 by means of an internal pull spring 29 which extends through the tubular passage provided by the said bar 26 and its attached arms 27 and 28, said spring having its ends 30 hooked over the extremities of the arms 27 and 28 so that the latter are pressed endwise toward the bar 26, and thus held in connected relation to the latter against displacement. The free ends of said arms 27 and 28 respectively project slightly outward through the respective openings 4 in the doll body. The ends of said arms 27 and 28 are closed by plugs 31 of cork, wood, or any other desirable material.

The reference character 32 indicates a skirt band which encircles the waist or lower body portion of the doll body, and from which depends the skirt member 33, which is made of any suitable material, but which is preferably made to imitate the straw or grass garment worn by Hawaiian hula dancers. The front central portion of the skirt band is pivotally attached by a pivot means 34 to the front side of the doll body, and is also pivotally connected by a pivot means 35 at the rear of the doll body. Preferably, I provide, in attached relation to the back of the doll body, a cover piece 36 which is fixed to the back of the doll body by its upper ends, so as to hang down over the opening 5 of said body to conceal the same; and to the lower end of said cover piece I pivotally attach the rear central portion of the skirt band. As thus disposed the skirt is pivoted to swing or oscillate from side to side. The sides of the skirt band, thus pivotally connected to the doll body, are attached to the ends of the arms 27 and 28 by fastening means 37 which penetrate the plugs 31.

The operation of the doll, constructed as above described, is as follows:—

The motor spring 11 is wound up to store the energy thereof. When the winding key is released, the motor spring begins to unwind, thereby causing the rotation of the driving gear 14 in an operative direction. The driving gear 14 imparts, through the intermediate train of pinions and gears 16, 17 and 19, a rotative movement to the escapement wheel 20. The rotation of the escapement wheel 20 acts upon the escapement dog or anchor 22 to produce an oscillation of the same, whereby the arbor 21 is rocked to in turn oscillate the lever 25. The lever 25 rocks the bar 26 and its arms 27 and 28, whereby the respective ends of the latter are caused to swing alternately up and down. The swinging or rocking movement of said arms 27 and 28 produce a rocking movement of the skirt band 32, thereby causing a side to side swaying or swinging movement of

the skirt 33. The rocking of the skirt band and swaying of the skirt produces the illusion of a hip or lower body movement of the doll, thus simulating the movements of the Hawaiian hula dance, and thus effecting a 70 very life-like, realistic and amusing rhythmic movement whereby the body of the doll appears to participate in the dance motion.

It will be understood that some changes may be made in the arrangements and combinations of the various devices and parts, as well as in the details of the construction of the same, without departing from the scope of the present invention as set forth in the foregoing specification, and as defined in 80 the appended claims. Hence, I do not limit this invention to the exact arrangements and combinations of the various devices and parts as described in said specification, nor do I confine myself to the exact details of 85 the construction of said parts as illustrated in the accompanying drawings.

I claim:—

1. In a doll of the kind described, a body having a chambered interior and provided in its lower trunk portion with laterally opposite side openings, a spring motor mechanism supported within said chambered interior, means oscillated by said spring motor mechanism having portions extending oppositely through said side openings, and a skirt member attached to said latter means adapted to be rhythmically swayed from side to side by the operation thereof.

2. In a doll of the kind described, a hollow body provided in its lower trunk portion with laterally opposite side openings, a spring motor mechanism supported within said body, means oscillated by said spring motor mechanism having portions extending oppositely through said side openings, a skirt member pivotally attached to said body so as to swing on a central axis extending from the front to the rear of said body, and said skirt member having its upper sides attached to the exterior ends of said oscillated means whereby the movement of the latter is imparted thereto.

3. In a doll of the kind described, a hollow body provided in its lower trunk portion with laterally opposite side openings, a transverse bar having oppositely extending arms within said body with the free ends thereof projecting through said side openings, a skirt member girding the lower portion of said body, said skirt member having its sides attached to said free ends of said bar, a pivoted transversely oscillatable lever with the free end of which said bar is connected, and a spring motor mechanism for actuating said lever.

4. In a doll of the kind described, a hollow body, provided in its lower trunk portion with laterally opposite side openings, a transverse bar having oppositely extending

arms within said body with the free ends thereof projecting through said side openings, a skirt member girding the lower portion of said body, said skirt member having 5 its sides attached to said free ends of said bar, a pivoted transversely oscillatable lever with the free end of which said bar is connected, an escapement mechanism for oscillating said lever, and a spring motor mechanism 10 for actuating said escapement mechanism.

5. In a doll of the kind described, a hollow body provided in its lower trunk portion with laterally opposite side openings, 15 a spring motor mechanism supported within said body, an escapement mechanism actuated by said spring motor mechanism, a

lever oscillated by said escapement mechanism, and a transverse means connected with the free end of said lever having opposite 20 free ends projecting respectively through said respective side openings, and a skirt member pivotally attached to said body so as to swing from side to side, said skirt member having its side portions attached to the free 25 ends of said transverse means.

In testimony that I claim the invention set forth above I have hereunto set my hand this 5th day of May, 1921.

DAVID ZAIDEN.
